UNITED STATES PATENT OFFICE.

HAROLD L. BURR, OF ROCKFORD, ILLINOIS.

DESIGN FOR A SHIRT.

Application filed January 19, 1927. Serial No. 20,434. Term of patent 7 years.

To all whom it may concern:

Be it known that I, HAROLD L. BURR, a citizen of the United States, residing at Rockford, in the county of Winnebago and State of Illinois, have invented a new, original, and ornamental Design for Shirt, of which the following is a specification, reference being had to the accompanying drawing, forming part thereof.

The invention comprises a shirt generally of the type called sweat shirts, wherein the sleeves have panels or gores inserted therein presenting contrasting appearances between the material of the inserts and the material of the shirt body and sleeves substantially as herein shown.

In the drawing, wherein I have represented the inserts by surface shading—

Figure 1 is a front view of a shirt showing my new design, one of the sleeves being disposed so as better to convey an impression of the appearance thereof; and

Figure 2 is a plan view with the sleeves spread out full length and laid flat still further illustrate my new design.

I claim:

The ornamental design for a shirt substantially as shown and described.

HAROLD L. BURR.
